UNITED STATES PATENT OFFICE.

JONAS R. FOSTER, OF STONEHAM, MASSACHUSETTS.

DESIGN FOR A PENCIL-SHARPENER.

SPECIFICATION forming part of Design No. 22,853, dated October 24, 1893.

Application filed November 25, 1892. Serial No. 453,138. Term of patent 7 years.

To all whom it may concern:

Be it known that I, JONAS R. FOSTER, a citizen of the United States, residing in Stoneham, in the county of Middlesex and State of Massachusetts, have invented and produced a new and original Design for Pencil-Sharpener, of which the following is a specification, reference being made to the accompanying drawings, forming a part thereof.

Figures 1, 2, and 3, represent different side elevations of my newly designed pencil sharpener, and Fig. 4, a top view of the pencil sharpener shown in Fig. 2.

The leading feature of my design consists in several continuous plane faces arranged side by side, and around the body of the sharpener from one end nearly to the opposite end thereof. These longitudinal plane

faces represented at *a*, have flat surfaces. The ends of said longitudinal plane faces are 20 slightly curved as at *b*. The sides of said longitudinal plane faces are herein shown as separated a short distance from each other, leaving a narrow defined division line between the said plane faces, as represented at *c*. 25

I claim—

The design for a pencil sharpener herein shown and described.

In testimony whereof I have signed my name to this specification in the presence of 30 two subscribing witnesses.

JONAS R. FOSTER.

Witnesses:

BERNICE J. NOYES,
LUCY F. GRAVES.
